(57) **CLAIM**

The ornamental design for a two-sided deck member, as shown and described.

DESCRIPTION

FIG. 1 is a top perspective view of the first embodiment of a two-sided deck member showing our new design; FIG. 2 is another top perspective view thereof; FIG. 3 is top view thereof; FIG. 4 is a side view thereof, the opposite side view being a mirror image thereof; FIG. 5 is an end view thereof, the opposite end view being a mirror image thereof; FIG. 6 is a bottom perspective view thereof; FIG. 7 is another bottom perspective view thereof; FIG. 8 is a bottom view thereof; FIG. 9 is an enlarged view thereof, taken from portion 9 shown in FIG. 3; FIG. 10 is a cross-sectional view thereof, taken along lines 10-10 shown in FIG. 1; FIG. 11 is a top perspective view of the second embodiment of the two-sided deck member showing our new design; FIG. 12 is another top perspective view thereof; FIG. 13 is a top view thereof; FIG. 14 is a first bottom perspective view thereof; FIG. 15 is another bottom perspective view thereof; and, FIG. 16 is bottom view thereof.

The dash-dash broken lines shown in FIGS. 1 and 3 are included to show a partial enlarged view only and form no part of the claimed design. The two-sided deck member in FIGS. 11 through 16 is shown with a symbolic break in its length and width. The appearance of any portion of the two-sided deck member between the break lines forms no part of the claimed design.
